(57) **CLAIM**

The ornamental design for a roller grill assembly canopy, as shown and described.

DESCRIPTION

FIG. 1 is a front perspective view of a roller grill assembly canopy showing my new design shown in a position of use with an exemplary roller grill assembly;

FIG. 2 is a front perspective view thereof, shown with the exemplary roller grill assembly removed to show aspects of the design not visible when combined;

FIG. 3 is a left side view thereof;

FIG. 4 is a right side view thereof;

FIG. 5 is a front view thereof;

FIG. 6 is a rear view thereof;

FIG. 7 is a top view thereof; and,

FIG. 8 is a bottom view thereof.

The broken lines are shown for the purpose of illustrating parts of the article that form no part of the claim.

1 Claim, 8 Drawing Sheets
